PRESTRESSED SUCKER ROD

Peter F. Rossmann, Morristown, N. J.

Application August 5, 1944, Serial No. 548,291

2 Claims. (Cl. 255—28)

1

The invention relates in general to long metal rods of general application, particularly to rods and similar articles designed to transmit axially directed loads, and the invention specifically relates to a unit of a fabricated sectional sucker rod such as is commonly used in mining and similar pumping machinery.

The primary object of the invention is to provide a metallic load receiving and transmitting rod or bar which will tend to decrease its elongation from zero to maximum load in use, and which will at the same time tend by reason of a deformation imposed thereon to increase its tensile strength and also to extend fatigue life.

In connection with the embodiment of the invention in a sucker rod or similar article where it is subjected while in use to alternate and recurrent tensile and compression stresses as in oil well pumping, it is known that the resultant stretch or elongation of such sucker rods is an undesirable factor with regard to the attaining of the requisite pumping and also influences the depth since the elongation produces waves in the rod especially when the depth is great. The speed of pumping is also a factor contributing to the short life of such rods.

The present disclosure features a method of treating sucker rod sections and like length of rods by stretching the same to place the rod under a predetermined axial deformation, retaining the elongation stresses so produced within the rod to resist further elongation of the rod within the limits of retained stresses, and thereafter to restrain any tendency of the rod to revert to its initial configuration during use.

Preferably the degree of deformation to which the rod is subjected is limited to obtain the best results, for it has been found that the stresses can be increased even beyond normal magnitudes by restraining the stress cycle to a very small stress range. For instance, in the case of sucker rods, the stress may be first changed from zero to 100,000 pounds per square inch and the fatigue life will be less than if the change were made subsequently from, say, 80,000 to 100,000 pounds per square inch by reason of conditions imposed thereon during use.

Various other objects and advantages of the invention will be in part obvious from a consideration of the method features of the disclosure (and from an inspection of the accompanying drawings) and in part will be more fully set forth in the following particular description of one method of practicing the invention, and the invention also consists in certain new and

2

novel modifications of the preferred method (and other features of construction and combination of parts) hereinafter set forth and claimed.

In the accompanying drawing:

5 Figure 1 is a portion of a sectional sucker rod illustrating in axial cross section a unit constituting a preferred embodiment of the invention and shown attached to the next two similar sections. In the several figures the mid-portions are broken away to reduce the length showing of the sections.

10 Figure 2 is a view in axial section of the component parts of the unit forming Figure 1 with its tension rod in its normal condition before it is stretched; and of the compression sleeve prior to being rolled into place, located in telescopic relation and illustrating the first step in the method of forming the complete article shown in Figure 1.

15 Figure 3 is a similar view of the parts shown in Figure 2 with the outer sleeve almost in its final position and illustrating the next step in the method of forming the completed showing in Figure 1.

20 Figure 4 is a longitudinal sectional view of a modified form of sucker rod section and which may be regarded as illustrating the component parts either in their stressed or unstressed condition, and

25 Figure 5 is a similar view of still another modification.

30 In the drawings and referring first to Figure 1, there is disclosed a sucker rod 10 formed of a plurality of similar units or sections 11. Each section includes a pair of telescoped elements 35 hereinafter sometimes referred to as an inner tension element or core 12 and an outer compression element or sleeve 13.

35 Referring to the tension element 12 as illustrated in its original or unstressed condition shown in Figures 2 and 3, there is disclosed a solid metal rod 12a, preferably of alloy steel, the midlength portion 14 of which is of a cross sectional area reduced from that of the end portions 15 and 16 to form the mid-portion as a long, relatively thin shank. Opposite ends of the shank coact with the adjacent enlarged end portions to form a pair of inwardly facing stop shoulders 17 and 18, disposed in parallel planes 40 at right angles to the axis of the core element. The end portion 15 is provided with a threaded socket 19 and the opposite end portion is reduced and forms an externally threaded stud 20. As shown in Figure 1, the stud of one section is 45 designed to be threaded into the socket of the

next adjacent section and a number of these sections coact to form a completed sucker rod following conventional practice in this respect.

It is a feature of this disclosure that the tension element 12 be slightly prestretched, as, for instance, from the distance measured between the planes $a'-b'$ and $c'-d'$ in Figures 2 and 3 to the increased length defined by the distance between the planes $a-b$ and $c-d$ of Figure 1. This stretching is attained by simply pulling the ends of 12a apart and thus away from each other as indicated by the double-headed arrow of Figure 1.

The tube 13a from which the sleeve 13 is formed has initially an internal diameter sufficient to permit it to slip over the enlarged end portions 15 or 16 and has a length slightly less than the axially measured distance between the stop shoulders 17-18 as seen in Figure 2. In order to bring the tube 13a into the reduced length of the finished form, it is subjected to a conventional tube reducing rolling operation under pressure sufficient to cause the tube finally to engage snugly the shank 14 with such axial elongation as will cause the ends 21 and 22 of the tube to bear against the stop shoulders 17-18 and in this way force them apart. Following conventional tube rolling operations, the squeeze rollers of a forming machine operate first on the two ends constricting the same towards the core provided by the shank portion of the stock 12a somewhat as suggested by the exaggerated showing in Figure 3. In the showing in Figure 3 it is assumed that the outer tube is just touching at its opposite ends, both the adjacent ends of the shank and the outer portions of the two shoulders. As the deforming rollers move from the ends of the tube towards the center they will effect a crowding of the tube forcefully in outward directions against the shoulders to force them apart and thus place the shank portion of rod 12 under tension particularly in the portion thereof between the planes $a-b$ and $c-d$. At the same time, while the inner member 14 is thus being deformed axially under tension, the rolling operation will deform the outer tube 13a under compression. In the resulting article as shown in Figure 1, the major portion of the core 12 is held with its stress trapped therein by the outer sleeve 13, the entire length of which is held with its stresses trapped therein by being squeezed between the shoulders 17 and 18 of the tension element 12.

While it is most convenient to use the shank as a mandrel on which to roll the tube, it is obvious that the tube need not snugly encircle the shank; it is simply necessary that it fit between and force apart the shoulders 17-18. It is within the scope of the disclosure to first stretch the core element 12 to deform the same axially and then roll the outer sleeve into place between the shoulders 17-18 either with the tube undeformed or preferably, deformed axially under compression before it is rolled into position between the shoulders.

Referring to the modified form of the invention shown in Figure 4, here again the unit forming the sucker rod section 23 is formed solely of two telescoped elements 24 and 25, of which the inner element 24 will sometimes hereinafter be referred to as a compression rod and the outer element 25 will be referred to as a tension member. The compression rod 24 is of one piece and comprises a long cylindrical portion 26 which constitutes the major portion of its length. The

outer end of the member 24 forms an externally threaded stud 27 and the part between the cylindrical portion and the stud is reduced in cross section to form a narrow shaft or waist 28.

5 The tension member 25 is provided with two coaxially disposed bores 29 and 30 of unequal length. The shorter bore 29 is internally threaded and provides a socket corresponding to the socket 19 of the preceding figures. The longer bore 30 is of sufficient length to contain therein substantially all of the compression rod 24 and the outer end of the bore 30 is internally threaded as shown at 31. The two bores are separated by an internal partition 32 which provides a stop wall surface 33 constituting the bottom of the bore 30. The surface 33 is engaged by the inner rounded end 34 of the compression member 24. The stud 27 is in threaded engagement with the threads at 31 and the stud is so dimensioned that when the parts 10 are in their final stressed position as shown in Figure 4, the portion of the stud which protrudes outwardly beyond the adjacent end of the tension member corresponds in size and function to the stud 20 of the preferred form. The stud 27 is provided at its outer end with a kerf 35 designed to be engaged by a screw driver or similar tool for rotating the compression member into bearing engagement against the stop wall surface of the tension member.

15 In operation, it will be understood that the compression member 24 with its initial unstressed and natural dimensions is inserted with its long cylindrical end in advance into the bore 30 and then by means of a turning tool engaging the kerf, the compression member is forced hard into engagement with the surface 33 of the wall 32 with a torque sufficiently to develop compression strains in the compression or core member 24 as indicated by the double-headed arrow in Figure 4. In 20 its reactive tendency to elongate the portion of tension member 25 between the stops provided by the partition 32 and the outer threaded end, the tension member 25 is elongated and thus placed under tension. It will be seen from this 25 construction that having so deformed both members axially, the inner core element under compression and the outer tubular element under tension, the parts will tend mutually to resist reversion of each other to their initial unstressed 30 conditions.

35 Referring to the second modified form of the invention shown in Figure 5, the disclosure resembles that of the section 11 shown in Figure 1 with corresponding parts having the same reference characters. In this case the end portion 16 has been omitted; stud 20 slightly elongated and a nut 36 threaded on stud 20 for bearing engagement with the adjacent end 37 of the sleeve 13. The nut may be regarded as an equivalent of the end portion 16 with the additional advantage that it is adjustable and the inner face 18' of the nut may be considered as the equivalent of the shoulder 18.

40 In this modification the sleeve is disclosed as 45 optionally having a loose fit on the core 12 and the tube, even in its initial unstressed form, need not have an internal diameter greater than the enlarged end for it may be slipped onto the smaller end of the core 12 before the nut is located in place. In Figure 5 the nut may be preset at any 50 point desired and sleeve 13 may be rolled into position endwise on stop shoulders 17 and 18' as has been described for the Figures 1-3 form of the invention. Otherwise the unstressed sleeve 55 may be located in place and the nut turned hard

against the tube end 37. As the nut is advanced after contact there will be developed a resulting deformation of the core member 12 under axial tension and an equal deformation of the sleeve 13 under axial compression as indicated by the headed arrows.

In the case of the preferred form of the invention as shown in Figure 1 and in the modified form shown in Figure 5, the axially squeezed restraining sleeve 13 will, by reason of its compression, act to restrain the tendency of the tension member 12 to revert to its length dimension when it was in its unstressed condition such as is shown in Figure 2. When the elements are prestressed as herein indicated, the stress characteristics will of course be limited in the Figure 1 showing between the shoulders 17-18; in the Figure 4 showing between the wall 33 and the threaded portion 31 and in the Figure 5 showing between the shoulders 17 and the nut 36. While the end portions are unstressed, they are relatively short compared to the over-all length of the section and besides are usually more massive than the shank portion therebetween and are thus less liable to disintegrate under prolonged fatigue. It will be noted that in all cases the entire section is within the axially projected outline of the parts which form the joints between adjacent sections as shown in Figure 1 so that the addition of the second element does not increase the presently known cross sectional area of conventional form of sucker rods or add mutually to their cost.

By utilizing composite rods of the characters illustrated, the tendency of the rods as a whole to elongate in use has been largely eliminated so that the rods at the end of an operation on which they are transmitting loads axially therethrough, even when the loaded transmissions are rapidly reversing themselves, will maintain their original lengths, and by reason of this elimination of rapidly recurring changes in internal stress conditions, the life of the rods is materially lengthened.

In the case of using the instant form of sucker rod sections, there has been eliminated, or at least reduced, the rapidly succeeding waves of compression and tension stresses so objectionable with known forms of sucker rods when used in deep well pumping or the like.

I claim:

1. A sucker rod section provided at opposite ends with elements of fastening means for securing the section to other similar sections to form a complete sucker rod, said section including a pair of elongated telescoped elements permanently secured together, each element formed in-

tegrally as one piece, one constituting a solid core element defined at opposite end portions with enlarged heads and forming therebetween a shank portion integral with the heads and of less cross section than its headed end portions, said shank portion forming with the said headed end portions a pair of inwardly facing non-rotative stop shoulders, said core element in the portion thereof between the shoulders being deformed under a preimposed tension and with the headed end portion not necessarily stressed, the other element constituting a retaining sleeve deformed under compression, fitting between the shoulders with its ends in fixed bearing engagement against the shoulders and acting resiliently in a tendency to spread them apart, and the said two elements at all times reacting on each other to maintain the elements so formed into their respective compressed and tensioned stress conditions and thus each acting to resist the return of the other to its initial length before it was deformed.

2. A composite sucker rod section having an inner core member provided with connecting means at its ends permitting a plurality of sections to be connected together to form a sucker rod of determinate length, spaced shoulders on said inner member extending radially outward adjacent each end thereof, a continuous outer tubular member surrounding said core member between said shoulders and bearing against said shoulders at its ends so as to maintain said core member under tension and said outer tubular member under compression irrespective of the rod section being connected to another section, whereby further elongation of said sucker rod section in operation is substantially prevented.
